KEY HOLDER

Dominic Di Noble, Detroit, Mich.

Application August 6, 1957, Serial No. 677,192

1 Claim. (Cl. 150—40)

This invention relates to key holders and more particularly to a key holder adapted to be carried in a pocket.

It is an object of the present invention to provide a simple and efficient key holder for carrying keys within pockets of clothing and the like which is devoid of any annoying protruding screws or metallic members so as to provide a minimum amount of discomfort to the individual carrying the holder.

It is another object of the present invention to provide a key holder of the above type that is very easy to handle when opening and locking doors, and which is substantially heat insulated so as to prevent discomfort because of high or low temperatures during use.

Other objects of the invention are to provide a key holder bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

Figure 1 is a top plan view of a key holder made in accordance with one form of the present invention in operative use;

Figure 2 is an end elevational view of the device shown in Figure 1; and

Figure 3 is a top plan view of a modified form of construction.

Referring now more in detail to the drawing, and more particularly to Figures 1 and 2 thereof, a key holder 10 made in accordance with one form of the present invention is shown to include a flexible cover member 12 that may be preferably constructed of plastic, or strong fabric. A spring clip 14 that is adapted to releasably support a key 15 is rotatably mounted at one end upon a pivot 17 that extends through a central portion of the cover member 12. With the key clip 14 in the position as shown in Figure 1, it will be noted that it does not extend outwardly beyond the adjacent edges of the cover member so that it does not become exposed during use.

The cover member 12 is foldable between the open position shown in Figure 1 to a closed position 10a so as to completely enclose the key clip and key 15 which has been rotated inwardly in the direction of the arrows. A male snap member 18 is secured to one end of the

2

cover member while a female snap member 19 is secured to the opposite end of the cover member, whereupon folding the ends of the cover member together, the snap fasteners may be secured together thus securing the assembly in the closed position 10a shown in Figure 1.

In Figure 3, a modified form of construction 20 is shown wherein the cover member 22 has a rivet 23 extending through a central portion thereof for rotatably supporting a pair of key clips 24, 25 therein. Each one of these clips 24, 25 supports a separate key 26, 27 for rotation between an enclosed and an exposed position. In the exposed position, it will be noted that the keys may be used without exposing the key clip portion of the device, in a manner quite similar to that discussed in connection with the embodiment disclosed in Figures 1 and 2. A similar snap fastener 28 is also provided to secure the parts in either the key exposed or key enclosed positions.

20 In both of the aforementioned embodiments, it will be noted that substantially none of the working parts of the key or clip are exposed so that when the device is carried within the pocket, there is very little possibility of damage to the pocket or discomfort to the wearer.

25 While various changes may be made in the detail construction, it shall be understood that such changes shall be within the spirit and scope of the present invention as defined by the appended claim.

30 What I claim as new and desire to protect by Letters Patent of the United States is:

A key holder comprising, in combination, a flexible cover member, a plurality of spring clips, each clip adapted for releasably supporting a single key, a single clip retaining member for pivotally supporting said clips 35 in sliding contact upon said cover member, said cover member being foldable between an open key exposing position and a key enclosed enveloping position, means for securing said cover in said closed key enveloping position, said single clip retaining member for pivotally supporting said clips to said cover member comprising a rivet extending through a central portion of said cover member and defining a pivotal bearing for said clips, said pivotal clips being maintained substantially in sliding contact with the central portion of said cover member and with their free ends movable between the ends of said cover member at all times, said means for securing said cover in said closed key enveloping position comprises a male and female snap fastener element secured each to an opposite end of said cover member, and the free ends of said clips extending normally away from each other in longitudinal alignment.
